UNITED STATES PATENT OFFICE.

ANDREW H. HAMMOND, OF WORCESTER, MASSACHUSETTS.

WINDING-ROLLER FOR MUSICAL INSTRUMENTS.

SPECIFICATION forming part of Letters Patent No. 271,064, dated January 23, 1883.

Application filed December 22, 1881. (No model.)

To all whom it may concern:

Be it known that I, ANDREW H. HAMMOND, of Worcester, in the county of Worcester and State of Massachusetts, have invented certain 5 new and useful Improvements in Winding-Rollers for Mechanical Musical Instruments, of which the following is a specification.

The object of my present improvements is to produce a roller on which a traveling music-sheet for a mechanical musical instrument may be wound, and which shall be so light as to acquire but little momentum when in motion. Such a roller is especially desirable as a take-up roller for the music-sheet.

15 My improvements consist in the combination, in a mechanical musical instrument, with a traveling music-sheet, of a roller composed of a wooden or other shaft and heads, and a body consisting of a cylindric shell, of paper or other light material.

They also consist in the combination, with such a music-sheet, of a roller composed of a wooden or other shaft provided with two heads and an intermediate flange or truck, and a 25 body consisting of a cylindric shell, of paper or other light material, and having a peripheral recess containing a device whereby the sheet may be attached.

In the accompanying drawings, Figure 1 30 represents a longitudinal section of a mechanical musical instrument containing rollers embodying my improvements. Fig. 2 is a top view of the case and rollers of the same, one of the rollers being partly in section; and Fig. 3 is 35 a longitudinal section of the case of the instrument, a side view of bearings for the rollers, and a transverse section of journals of the rollers in the bearings.

Similar letters of reference designate corresponding parts in all the figures.

A designates the case of a mechanical musical instrument. B designates the reed-board thereof. C designates the traveling perforated music-sheet. D designates the roller on 45 which the music-sheet is normally kept wound, and E designates the take-up roller on which the music-sheet is wound during the playing of the instrument.

The take-up roller E consists of a shaft, a, 50 of wood or other suitable material, two heads, b, affixed thereto, hubs c, contiguous to the

heads, and preferably made integral therewith, an intermediate flange or truck, d, and a cylindric body or drum, e, of paper or other light material, fitting the said hubs and flange 55 or truck.

In the periphery of the flange or truck d and adjacent part of the body or drum e is a recess, f, provided near the bottom with a hook, g, for detachably securing the music-sheet thereto. The end of the music-sheet is preferably provided with a ring, h, capable of engagement with the hook g, and this ring may be secured to the music-sheet by a tape or strip, of any strong thin material, passing 65 through the ring, and lapped over each side of and secured by paste, glue, or otherwise to the music-sheet.

I prefer to make the heads of the music-roller D of paper, binders' board, leather-board, or like material, for in that way I can easily and cheaply make them strong and durable. They project circumferentially beyond the body of the roller. One or both the heads 70 of the take-up roller E may be made in the 75 same manner, if desirable.

The heads of the rollers used in mechanical musical instruments and certain other articles are necessarily so thin that when made of wood they are easily split and broken; but by 80 making them of paper, binders' board, leather-board, or like material this difficulty is obviated. Where used they are pressed onto extensions of the shaft or body of the rollers, made of less diameter than the shafts or bodies 85 themselves, and glued against the shoulders thus formed. Motion may be transmitted to these rollers by any suitable means acting on the heads of the rollers, or otherwise.

These music and take-up rollers are shown 90 as having their journals supported in bearings composed severally of a fixed block, I, secured to the case A, and a movable cap, I', pivoted at i, and held upon the block I by means of a spring, l². In the edge of the blocks I are 95 formed notches or recesses j, which receive the journals, and in which the journals are retained by the pivoted caps I'. The opposite faces of the blocks and caps diverge, as at k, beyond the notches j, thus enabling a roller-100 journal to be placed between such diverging portions, and then inserted in the notch by

simply pushing it down or into it, the cap I' being forced away from the block I by the pressure exerted upon it by the journal, and after the entrance of the journal into the notch 5 returning to hold the journal in the notch. The caps I' of these bearings bear directly on the journals of the rollers and exert friction thereon, which will prevent the rollers from moving too rapidly, or from moving at all 10 when they are not desired to move.

When a roller is to be removed it has only to be pulled outward with a little force, and hence it will be seen that the roller may be either inserted or removed without any necessity for manipulating the bearings.

What I claim as my invention, and desire to secure by Letters Patent, is—

1. In a mechanical musical instrument, the

combination, with a traveling music-sheet, of a roller composed of a wooden or other shaft 20 and heads, and a body consisting of a cylindric shell, of paper or other light material, substantially as specified.

2. In a mechanical musical instrument, the combination, with a traveling music-sheet, of a roller composed of a wooden or other shaft, provided with two heads and an intermediate flange or truck, and a body consisting of a cylindric shell, of paper or other light material, and having a peripherical recess containing a 30 device for the attachment of said music-sheet, substantially as specified.

A. H. HAMMOND.
